UNITED STATES PATENT OFFICE.

WILLIAM L. JONES, OF PARKVIEW, NEW JERSEY.

MACHINE FOR ROLLING GEARS.

SPECIFICATION forming part of Letters Patent No. 716,241, dated December 16, 1902.

Application filed October 5, 1901. Serial No. 77,693. (No model.)

To all whom it may concern:

Be it known that I, WILLIAM L. JONES, a citizen of the United States, residing at Parkview, in the county of Essex and State of New Jersey, have invented a certain new and useful Improved Machine for Rolling Gears, of which the following is a description.

My invention relates to an improved machine for making a gear from a cast or wrought blank by a rolling operation, whereby the resulting article will be as perfect as a cut gear and will possess the strength and durability of a compressed gear.

It has been proposed in the manufacture of pinions of relatively small size to subject the hot billet to such an enormous pressure by the action of a punch in a female die that the metal will be displaced and caused to enter the teeth cut in such die to form a complete compressed pinion. In carrying on such an operation enormous pressures are necessary, involving expensive machines and operations, while the possible diameter of the gear which can be made by such a process is necessarily limited.

With my present apparatus I am enabled to make a compressed gear or a gear that possesses all the advantages of a compressed gear of any desired diameter and at relatively low cost.

In carrying the invention into effect I employ a suitable female die, which may be made sectional or not and which is formed on its interior with the desired contour in negative to be given to the complete article. Within this die is placed a blank, either cast or wrought, the teeth of which fit more or less closely within the corresponding recesses of the die. The rim of the blank so formed is made thicker than is desired in the complete article. Such a blank being suitably heated and the blank and rollers being moved relatively, the rollers tend to reduce the thickness of the rim, so as to displace the metal and force the teeth of the blank intimately into engagement with the corresponding recesses of the die. In this way the resulting gear will be formed with perfect teeth, and the metal having been subjected to powerful compression will be tougher and more durable than is the case with either cast or cut gears. At the same time since the displacement of the metal is

effected by the action of rollers which effect their operation progressively the gears can be constructed in simpler and cheaper machines and at a lower cost than if the displacing pressure is applied simultaneously to all portions of the gear. 55

In order that the invention may be better understood, attention is directed to the accompanying drawings, forming part of this specification, and in which—

Figure 1 is a plan view of a suitable machine embodying my invention; Fig. 2, a side elevation thereof; Fig. 3, a plan view of a portion of the machine, illustrating the employment of six compressing-rollers; Fig. 4, a section on the line 4 4 of Fig. 3; Fig. 5, a sectional view, on an enlarged scale, through the female die and the parts which support it; Fig. 6, a section on the line 6 6 of Fig. 5; Fig. 7, a section on the line 7 7 of Fig. 5; Fig. 8, a separate sectional view of a suitable blank for use with the improved machine, and Figs. 9, 10, 11, and 12 are detail views of a modification of the table. 75

In all of the above views corresponding parts are represented by the same numerals of reference.

A suitable base 1 supports two heavy housings 2 3, having guides 4 4 on their inner faces. Vertically movable in these guides is a bed 5, which is carried on screws 6, which latter are in turn sustained by lugs 7, cast to the housings 2 3. The screws 6 are simultaneously rotated through bevel-gearing 8 from an auxiliary shaft 9, carrying tight and loose pulleys 10 and driven from any suitable source of power. Mounted to rotate on the bed 5 is a table 11, antifriction-balls 12 being 80 preferably interposed between the two to reduce friction. The table 11 is provided with an exterior beveled rack 13, with which a pinion 14 meshes, the latter being carried on the main driving-shaft 15, having a fly-wheel 16 at its end and having tight and loose pulleys 17. Carried by the table 11 is a female die 18, the interior of which is cut or otherwise formed to represent in negative the gear which is to be produced. Preferably this female die is made sectional, so that after a gear has been formed the sections of the die may be separated to permit the gear to be easily removed; but the die need not be made 85 90 95 100

sectional and may be continuous, the gear being removed after it has slightly contracted on cooling by a direct longitudinal movement either from above or below. In the drawings I illustrate the die as being formed of a series of radial sections which coöperate together, each section being provided with a depending lug 19, which works in a spiral groove 20 in an adjusting-plate 21, the latter being carried directly on the table 11 and being rotatable independently thereof by means of a lever 22. It will be obvious that by partially rotating the adjusting-plate 21 the sections of the die will be simultaneously moved radially toward and away from each other to open or close the die. Mounted above the adjusting-plate 21 is a stationary plate 23, supported on two pedestals 24, whereby the operating-lever 22 may work between said pedestals to give the desired partial rotary movement of the adjusting-plate 21. The plate 23 is provided with slots 25 therein, in which work the lugs 19, which depend downwardly from the sections of the die and which coöperate with the spiral groove 20 in the adjusting-plate 21. In order to properly guide the sections of the die, I employ an annular plate 26 above the same, which plate is provided with spacing-sleeves 27, through which bolts 28 extend, whereby all the parts will be held firmly together, as will be understood. Mounted in slots in the housings 23, so as to be vertically movable therein, is a frame 29, suitably supported by a truss 30, so as to be of very rigid construction. Carried by this frame are hangers 31, which carry the flanged compressing-rollers 32. The hangers are adjustable radially in the frame 29 by screws 33, provided with integral collars 34, which work between the outside of the frame 29 and suitable notched plates 35, screwed to said frame, whereby by rotating the screws 33 the hangers 31 may be adjusted radially in either direction. When once adjusted, the hangers 45 may be locked rigidly in position by bolts 36. In Fig. 1 I show the frame as being provided (in dotted lines) with two of the compressing-rollers 32, while in Figs. 3 and 4 I illustrate the frame adapted to receive six of these 50 rollers. Obviously any number of the compressing-rollers may be employed. During the work of rolling the gear within the die the frame 29, carrying the compressing-rollers, is moved downward to displace the metal of the blank, as will be explained. This movement may be imparted to the frame in any suitable way, but preferably it is derived from the power which rotates the die relatively to the compressing-rollers. I therefore preferably 55 make use of a pair of heavy connecting-rods 37, which are attached at their upper ends to knuckles 38, which extend out from the frame 29 and work in the slots in the housings 23 and which connecting-rods at their lower ends are 60 formed with eccentric-straps 39, which engage over eccentrics 40 on a counter-shaft 41. For the purpose of adjusting the connecting-rods

37 they are provided with turnbuckles 42 therein, and in order that the connecting-rod at the left, Fig. 3, may pass the shaft 15 it is 70 provided with a loop, as shown, through which the shaft may extend. The counter-shaft 41 at its outer end is carried by a bearing 43, between which and the housing 2 it is provided with a worm-gear 44. This worm-gear 75 is driven by a worm 45 on a short shaft 46, carried in suitable bearings 47 from the housing 2. The main power-shaft 15 is provided with a pinion 48, meshing with a spur-gear 49 on a short shaft which is mounted in bearings 50, and by means of bevel-gearing 51 power is transmitted from the gear 49 to the shaft 46.

The form of blank on which I operate with my improved machine is illustrated particularly in Fig. 8, showing the same in cross-section, although in Fig. 6 I illustrate (in dotted lines) the blank in position within the female die in order that its relative shape and size may be understood. Referring to Fig. 8, I 85 illustrate the blank as having a rim 52, formed with teeth 53, which fit in the corresponding recesses formed in the female die, preferably with a relatively close fit, with a web 54, either closed or open to constitute spokes, and with 90 a hub 55. The rim 52 of the blank is made thicker than is desired on the finished gear and preferably is formed with two curved ribs 56 to offer the desired additional metal, which in the carrying on of the process is 100 displaced into the gear-teeth. The hub may be made hollow or solid, as is desired, in the latter case being bored out after the gear is formed. The blank of substantially the form indicated is preferably cast, although obviously it may be wrought or otherwise produced. The top of the plate 23 is provided with an annular shoulder 57, the periphery of which conforms with the interior of the rim of the wheel and, together with the flanges 110 of the rollers 32, prevents the metal under compression from spreading inwardly, thus forcing all of the surplus metal into intimate contact with the teeth of the female die 18.

In Figs. 9, 10, 11, and 12 I show a modification of the annular shoulder 57, in which the shoulder is made adjustable, so as to provide for the contraction of the same to allow for the ready removal of the finished gear. In this modification the plate 23 is shown as 115 having a central circular recess, in which is seated a plate 58, having radial shouldered slots 59, in each of which is mounted a sliding block 60, provided with a segmental wing 61 and a projecting tongue 62, which completely fills the slot 59 under the wheel to be compressed. In the inner end of each slot is 120 adjustably secured an anchor-block 63, and connecting the anchor-block and the sliding block 60 is a toggle-joint 64, provided with an operating-handle 65 for moving the blocks 60 and wings 61 from contact with the completed wheel to allow for the ready removal thereof 130 from the machine.

In operating my improved rolling-machine I take a blank of suitable form, heat it to the desired temperature, and place it within the female die 18 from above, so that it rests on the top of the perforated plate 23. Before the blank is thus inserted in the female die the bed 5, carrying the table and die with it, is lowered by the screws 6, and after the blank is in place these parts are returned to their normal position, engaging the bevel-gear 14 with the rack 13, the compressing-rollers 32 being also or substantially in engagement with the work and said rollers being in their uppermost position. Power is now applied to the shaft 15, and through the gearing 13 14 the table 11 is rotated with respect to the bed, so that the blank will be moved beneath the compressing-rollers 32. Through the gearing 48, 49, 51, 45, and 44 the shaft 41 will be slowly rotated, and by means of the connecting-rods 37 the frame 29 will be moved slowly downward, forcing the compressing-rollers into the blank and imposing the desired heavy pressure on the metal, so as to displace the ribs 56 or to otherwise flatten the rim, and thereby cause the metal forming the teeth of the blank to be forced intimately into contact with the corresponding recesses in the die, whereby the teeth on the finished gear 30 will be completely and accurately formed. By thus subjecting the rim of the blank to heavy compression the metal thereof will be made as tough as with a compressed wrought gear, while all the accuracy of a cut gear will 35 be secured. By adjusting the compressing-rollers 32 radially the machine can be made to operate on gears of different sizes, it being only necessary to make use of proper female dies for the purpose. After the shaft 41 has 40 made a complete half-turn the frame 29 will obviously commence to ascend, so as to relieve the pressure on the gear, and the screws 6 are then reversed to lower the bed 5 and permit the finished gear to be removed, which 45 can be done either by opening the sections of the female die, if the latter be sectional, or by forcing the gear out of the same by a direct longitudinal movement.

I prefer to make the compressing-rollers 50 with flanges and the plate with a stationary or a movable shoulder, as shown, in order to prevent the displaced metal of the blank from flowing inwardly toward the hub instead of outwardly toward the periphery; but with 55 blanks of certain forms such flanges may be dispensed with.

Having now described my invention, what I claim as new, and desire to secure by Letters Patent, is as follows:

1. In a machine for rolling gears, the combination with a toothed female die in which a gear-blank is carried, of a compressing-roller coöperating with said die for displacing the metal of the blank therein, and means for relatively moving said die and compressing-roller, substantially as set forth.

2. In a machine for rolling gears, the com-

bination with a toothed female die in which a gear-blank is carried, of a radially-adjustable compressing-roller coöperating with said die for displacing the metal of the blank therein, and means for relatively moving said die and compressing-roller, substantially as set forth. 70

3. In a machine for rolling gears, the combination with a toothed female die in which a gear-blank is carried, of a series of compressing-rollers coöperating with said die for displacing the metal of the blank therein, and means for relatively moving said die and compressing-rollers, substantially as set forth. 75

4. In a machine for rolling gears, the combination with a toothed female die in which a gear-blank is carried, of a series of radially-adjustable compressing-rollers coöperating with said die for displacing the metal of the blank therein, and means for relatively moving said die and compressing-rollers, substantially as set forth. 80

5. In a rolling-machine for the purpose described, the combination with a sectional female die in which a blank is carried, of a compressing-roller coöperating with said die for displacing the metal of the blank therein, and means for relatively moving said die and compressing-roller, substantially as set forth. 90

6. In a rolling-machine for the purpose described, the combination with a sectional female die in which a blank is carried, of a radially-adjustable compressing-roller coöperating with said die for displacing the metal of the blank therein, and means for relatively moving said die and compressing-roller, substantially as set forth. 100

7. In a machine for rolling gears, the combination of a toothed female die for containing a gear-blank, a compressing-roller coöperating with said die for engaging the blank and compressing the latter in said die, means for relatively moving the die and said roller to cause the roller to engage successive portions of the blank, and means for moving the roller toward the die to displace the metal of the blank, substantially as set forth. 105

8. In a rolling-machine for the purpose described, the combination of a female die for containing a blank, a compressing-roller coöperating with said die for engaging the blank and compressing the latter in said die, means for relatively moving the die and said roller to cause the roller to engage successive portions of the blank, means for moving the roller toward the die to displace the metal of the blank, and means for adjusting the die toward and away from the compressing-roller, 110 120 125 substantially as set forth.

9. In a rolling-machine for the purpose described, the combination with a rotatable table and a female die carried thereon, of a non-rotatable frame, a compressing-roller carried by said frame and coöperating with the die, and means for rotating said table, substantially as set forth. 130

10. In a rolling-machine for the purpose de-

scribed, the combination with a rotatable table and a female die carried thereon, of a non-rotatable frame, a compressing-roller carried by said frame and coöperating with the die, means for rotating said table, and means for moving the frame toward and away from the die to engage the roller with the blank, substantially as set forth.

11. In a rolling-machine for the purpose described, the combination with a rotatable table and a female die carried thereon, of a non-rotatable frame, a compressing-roller carried by said frame and coöperating with the die, means for rotating said table, means for moving the frame toward and away from the die to engage the roller with the blank, and means for adjusting the table vertically with respect to said frame, substantially as set forth.
12. In a rolling-machine for the purpose described, the combination with a sectional female die in which a blank is carried, of a series of compressing-rollers coöperating with said die for displacing the metal of the blank therein, and means for relatively moving said die and compressing-rollers, substantially as set forth.
13. In a rolling-machine for the purpose described, the combination with a sectional female die in which a blank is carried, of a series of radially-adjustable compressing-rollers coöperating with said die for displacing the metal of the blank therein, and means for relatively moving said die and compressing-rollers, substantially as set forth.
14. In a rolling-machine for the purpose de-

scribed, the combination with a rotatable table, and a female die carried by said table, of a non-rotatable frame, a compressing-roller carried by said frame and coöperating with the die, means for rotating said table, means for moving the frame toward and away from the die to engage the roller with the blank, and means for adjusting the table vertically with respect to said frame, substantially as set forth.

15. In a rolling-machine for the purpose described, the combination with a rotatable table, and a sectional female die carried by said table, of a non-rotatable frame, a compressing-roller carried by said frame and coöperating with the die, means for rotating said table, means for moving the frame toward and away from the die to engage the roller with the blank, and means for adjusting the table vertically with respect to said frame, substantially as set forth.

16. In a rolling-machine, the combination with a table, and a die carried thereby for containing a blank, of a compressing-roller, means for adjusting said compressing-roller radially, means for effecting a relative rotation of the roller and die, and means for effecting a relative movement between the roller and die toward and away from each other, substantially as set forth.

This specification signed and witnessed this 12th day of September, 1901.
